US0D1102551S

(12) **United States Design Patent** (10) Patent No.: **US D1,102,551 S**
(45) Date of Patent: ** Nov. 18, 2025

(54) **FLOW REGULATOR**

(71) Applicant: **Neoperl GmbH**, Mullheim (DE)

(72) Inventor: **Gerhard Blum**, Gutach (DE)

(73) Assignee: **Neoperl GmbH**, Müllheim (DE)

(**) Term: **15 Years**

(21) Appl. No.: **29/841,148**

(22) Filed: **Jun. 3, 2022**

Related U.S. Application Data

(62) Division of application No. 29/694,627, filed on Jun. 12, 2019, now Pat. No. Des. 960,291, which is a division of application No. 29/617,139, filed on Sep. 12, 2017, now Pat. No. Des. 855,756, which is a division of application No. 29/556,061, filed on Feb. 26, 2016, now Pat. No. Des. 800,867, which is a division of application No. 29/493,357, filed on Jun. 9, 2014, now Pat. No. Des. 754,282, which is a division of application No. 29/460,842, filed on Jul. 16, 2013, now Pat. No. Des. 709,593, which is a division of application No. 29/392,775, filed on May 26, 2011, now Pat. No. Des. 690,797.
